RUPTURE RELIEF BELT

Lewis A. Fritsch, Cincinnati, Ohio

Application October 3, 1933, Serial No. 692,015

3 Claims. (Cl. 128—100)

One object of the present invention is to provide a device of the class described, in which the pads may be detached in a few seconds of time, from the belt, without the aid of a screw driver or any tool, simply by the manipulation of a lock under the control of the thumb and the forefinger. So far as I am advised as to the state of the art, and as a result of my experience, extending over a period of about thirty years, all 5 trusses and belts for rupture have been made heretofore, in such a way that the pad is held on the body of the belt by means of one or two screws. Such a construction requires the use of a screw driver, and anywhere from three-quarters 10 of a minute upward is required to detach or attach the pad.

In view of the foregoing, one object of the present invention is to provide novel means for mounting the pads adjustably and removably on the belt, other objects being to provide a belt which can be taken apart readily for washing, to provide novel means for holding the belt in place on the body of the wearer, and, generally, to improve and enhance the utility of devices of that 20 sort to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention. 30

In the accompanying drawing:

Fig. 1 shows in rear elevation, a device constructed in accordance with the invention;

Fig. 2 is a top plan showing the device partly 40 in condition to be placed about the body of the wearer, the view illustrating the construction of the belt, and no attempt being made to depict the article as it will appear when in use;

Fig. 3 is a section on the line 3—3 of Fig. 1;

Fig. 4 is an elevation of the spring plate;

Fig. 5 is a fragmental view showing a portion of the body of the belt;

Fig. 6 is a sectional view of the separable fastener that holds the pad in place and forms an 50 anchorage for the ends of the belt;

Fig. 7 is an elevation of the flexible ring that cooperates with the pad.

The belt, as a whole, is marked by the numeral 1, and is made of flexible material. The belt 1 55 comprises a front piece 2, somewhat wider in its

intermediate portion than at its ends, and constructed of canvas or the like. In one end portion of the body 2 there is an opening 3, in the form of a transverse slit. Elastic straps 4 and 5 are connected to the ends of the body 2, adjustably and removably, by any suitable means, such as buckles 6. Couplings in the form of eyes 7 are provided and are connected to the ends of the straps 4 and 5, for adjustment longitudinally of the straps, by any desired means, for instance, through the instrumentality of cam buckles 8.

The front part of the body 2 of the belt 1 is supplied with a pocket designated by the numeral 9 in Fig. 3. This pocket is formed by a patch 10. The patch 10 is secured along its lower edge to the body 2 by a bottom stitching shown at 11. Upper stitching 12 connect the patch 10 to the body 2. At a single place intermediate its ends, the upper edge of the patch 10 is connected to the body 2, as shown at 14. The pocket 9, in view of the foregoing, is open at the top, saving for the connection shown at 14, and the ends of the pocket are open also. A reinforcing strip 15, shown in Fig. 3, may be applied to the outer surface of the body 2, intermediate the ends of the pocket 9, the reinforcing strip extending from the upper edge of the body to the lower edge thereof and being secured to the body. 20

The patch 10 that forms the pocket 9 is provided with openings 16, located side by side, the edges of the openings being suitably bound, for reinforcement. 30

The numeral 17 designates, in Fig. 4, a resilient metal plate, preferably made of spring steel, 35 and bowed slightly, from end to end, as indicated in Fig. 3. The plate 17 is widest at its ends and tapers toward its central portion, as Fig. 4 will show. Near to its ends, the plate 17 has central holes 18, with other holes 19 arranged thereabout. The plate 17 can be introduced into the pocket 9 through the upper, open edge of the pocket. The body 2 has central holes 20, as shown in Fig. 5, and other holes 21 are formed in the body, about the central holes 20. The holes 20 40 of the body 2 register with the holes 18 of the plate 17, and the holes 21 of the body 2 register with the holes 19 of the plate 17. This is clearly shown in Fig. 3.

Pads 22 are located in the pocket 9, and abut 50 against the spring plate 17. Flexible rings 23, made of leather, if desired, are disposed in the pocket 9, about the pads 22. Cover pieces 24 are secured to the rings 23, and extend across the openings in the rings. The cover pieces 24 are 55

made of material, preferably textile material, which will stretch, the cover pieces being considerably more yieldable than are the rings 23, the rings being flexible, but having no tendency to stretch.

5 As shown in Fig. 6, separable connectors are provided. They comprise a spearhead prong 25, secured to the pad 22, and extended through the hole 18 of the plate 17 and through the hole 20 of the body 2 of the belt 1, a button 26 having a neck 27 receiving the prong 25 and journaled in the hole 20 of the body 2, and a key 28 slidable on the button 26 and including spring arms 29 adapted to engage the prong 25, to hold the button 26 detachably on the prong, the key 28 being outwardly movable to the position of Fig. 6, to release the hold of the arms 29 on the prong 25. The buttons 26 are located on the outside of the body 2 of the belt 1, as Fig. 2 will show.

10 The belt is placed around the body of the wearer, in the position roughly and diagrammatically shown in Fig. 2. The elastic strap 5 is run through the opening 3 of the body 2 to bring the end of the strap 5 on the outside of the body, the straps 5 and 4 extending in opposite directions. The eyes 7 then are mounted over the buttons 26. The buttons 26, therefore, have two offices. First, they form part of the pad-securing means, and, secondly, they make a place of 15 anchorage for the ends of the elastic straps 4. The length of the straps 4 and 5 may be adjusted by shifting them in the buckles 6. The buckles 8 afford an adjustment for the eyes 7. The spring plate 17 yields and conforms to the body 30 of the wearer. The pads 22 bulge the cover pieces 24 outwardly through the openings 16 of the patch 10, as shown in Fig. 3.

15 The separable fastening of Fig. 6 renders it possible for the operator to detach the pad 22 in an instant, without the use of tools. The elastic straps 4 and 5 may be taken off to enable the body 2 of the belt to be washed, and when the belt is to be washed, the plate 17, the pads, and the rings 23 are removed. The stretchable cover pieces 24, in combination with the flexible but 20 inelastic rings 23, aid in holding the pads 22 in place. Because the material used at 24 is stretchable, and elastic, the parts 24 will conform readily to pads of different sizes. The pads may 25 be adjusted with respect to the plate 17 and the body 2 of the belt, by putting the prong 25 of Fig. 6 in the openings 19 and 21, rather than in the openings 18 and 20.

The article is so constructed that it will afford ease and comfort whilst the wearer is stooping, walking, climbing, or engaging in any other activities, and perineal straps are unnecessary to hold the belt down in place.

Having thus described the invention, what is claimed is:

1. A rupture relief appliance comprising a belt having ends, pads on the intermediate portion of the belt, separable fasteners extending through the belt and holding the pads on the belt and comprising parts exposed on the front of the belt, the ends of the belt having means for detachably connecting said ends with said exposed parts of the separable fasteners, a member secured to the inner surface of the belt, intermediate the ends of the belt, and forming a pocket on the belt, said member having openings, the pads extending through the openings, and a spring plate removably mounted in the pocket, the separable fasteners connecting the pads to the plate.

2. A rupture relief appliance comprising a belt having ends, pads on the intermediate portion of the belt, separable fasteners extending through the belt and holding the pads on the belt and comprising parts exposed on the front of the belt, the ends of the belt having means for detachably connecting said ends with said exposed parts of the separable fasteners, a member on the belt and forming a pocket on the belt, said member having openings, the pads extending through the openings, a spring plate removably mounted in the pocket, the separable fasteners connecting the pads to the plate, flexible inelastic rings removably mounted in the pockets and surrounding the pads, and elastic cover pieces carried by the rings and stretched through the openings by the pads.

3. A rupture relief belt having a wall which forms an open pocket, the wall being provided with an opening, a spring plate removably mounted in the pocket, a pad in the pocket and projecting through the opening, a flexible inelastic ring in the pocket and surrounding the pad, an elastic cover piece carried by the ring and bulged through the opening by the pad, and a fastener comprising separable parts mounted respectively on the pad and on the belt, one of said separable parts passing through the plate.
